JOSEPH MENCHEN, OF NEW YORK, N. Y.

AERIAL TORPEDO AND LAUNCHING MEANS.

1,382,375.

Specification of Letters Patent. Patented June 21, 1921.

Application filed April 13, 1918. Serial No. 228,343.

To all whom it may concern:

Be it known that I, JOSEPH MENCHEN, a citizen of the United States, and a resident of the borough of Manhattan, in the city, county, and State of New York, have invented new and useful Improvements in Aerial Torpedoes and Launching Means, of which the following is a specification.

The invention relates to aerial torpedoes, to means for carrying the same on and launching them from airplanes, to firing means therefor and means for controlling the same, and to various features and aspects of such matters which will become apparent. Among the objects are to enable a number of bombs to be disposed advantageously on the plane and to be released conveniently and with certainty by the pilot or occupant, to insure safety during handling and while on the plane and against failure to explode when dropped, to provide effective and readily adjustable means for timing the explosion, and to insure explosion in event of the bomb encountering either a substantially unyielding obstacle, such as a building, or a relatively yielding body such as another aeroplane or a Zeppelin or a net. The preferred embodiment of the invention will now be described, but it will be understood that various equivalent constructions may be devised.

In the drawings:

Figure 1 is a side elevation of one of the torpedoes in its carrying frame, the intermediate and major portions of the torpedo and frame being broken away for economy of space and dotted lines being used to illustrate the shifted position of the releasing parts;

Fig. 2 is a view looking at the right-hand end of Fig. 1;

Fig. 3 is a fragmentary bottom plan view of the right-hand portion of Fig. 1, dotted lines again showing the shifted position of the releasing parts;

Fig. 4 is a view, partly in bottom plan and partly in section, of an alternative releasing construction;

Fig. 5 is a fragmentary view looking at the opposite side of Fig. 4;

Fig. 6 is a large sectional plan view of the portions of the fixture at the rear end of the torpedo and of the co-operative parts carried by the torpedo, the body of the torpedo itself not being shown;

Fig. 7 is a rear sectional face view of the fuse holder disk;

Fig. 8 is a horizontal section through the left-hand portion of Fig. 6;

Fig. 9 is a sectional elevation of the firing mechanism at the forward end of the torpedo;

Fig. 10 is a side elevation of the parts shown in Fig. 6 in the normal or carrying position and showing the timing mechanism in a shifted position, the body of the torpedo being omitted from the illustration;

Fig. 11 is a vertical longitudinal section through the same parts shown in the act of swinging downward with the torpedo, the body of which, however, is not shown;

Fig. 12 is a view showing the parts carried by the torpedo dropping away from the fixture, a portion of the body of the torpedo being indicated by dotted lines;

Fig. 13 is a semi-diagrammatic view showing a preferred arrangement of the torpedoes on the plane;

Fig. 14 is a view similar to Fig. 10, partly broken away and in section, showing a modified construction;

Fig. 15 is a sectional plan taken on the line 15—15 of Fig. 14;

Fig. 16 is a perspective view of the hinged pintle shown in the last two views;

Fig. 17 is a perspective view of the rear portion of the rear stem of the torpedo; and

Fig. 18 is a face view of the cap holder and safety pin of the timing mechanism.

The torpedoes are carried horizontally, preferably four on a plane, two at each side of and above the pilot's seat, one in front and the other in rear, (see Fig. 13). The framework for supporting one of the torpedoes is seen more particularly in Fig. 1.

From a member 2 forming part of the framework of the machine depends a fixed hanger iron 3 braced by diagonal pieces 4. This hanger supports the rear end of the torpedo 5; and in each instance this rear end is disposed toward the pilot, the two hangers 3 at each side being adjacent each other and the supports for the forward ends of the torpedoes being remote. The rear end of each torpedo is hinged or pivoted to its hanger 3, so that when its front end is released the torpedo swings down. The said forward end is supported and held by laterally spaced members 6 projecting downward from the part 2 and by a withdraw-

able rest 7, in the form of a lever. A front stem 8 on the torpedo is received between the members 6 and bears downward upon the lever 7, which is pivoted at 9 beneath one of the members and crosses the bottom of the recess between them, being movable in a horizontal plane away from the hanger 3 in order to release the bomb. As indicated at 10, the portion of the edge of the lever 10 from which said front stem escapes when the supporting lever is withdrawn may be diagonal, so that the angular movement of the lever will bring it true with the end of the stem at the moment of release.

15 The supporting lever 7 is operated by a vertically disposed releasing hand lever 11, disposed adjacent the support 3 for the opposite end of the torpedo, the four handles being thus within easy reach of the pilot.

20 The hand grip of this lever is on its lower end, and its fulcrum pivot 12 is intermediate its ends, connecting it to a suitable hanger or fixed bracket 13. Its upper end is pivotally connected to one end of a slide 14, which 25 is movable horizontally upon the upper part of the framework. The pivot pin 15 is guided in a horizontal slot 16 in the fixed structure, and the opposite end of the slide is provided with another guide slot 17 which 30 slides upon a fixed pin 18. The fulcrum portion of the hand lever is preferably slotted, at 19, to allow for the difference in movement of the parts. The end of the slide remote from the hand lever has a downwardly extending part 20, to which the free 35 end of the supporting lever 7 is connected, so that movement of the slide by the hand lever in the direction of the forward end of the torpedo withdraws the rest for said end, 40 permitting it to hinge downward on the hanger 3.

Figs. 4 and 5 show an alternative releasing arrangement. Here the supporting lever 7^a is connected to a stem 90 passing outward 45 from a flexibly supported cylinder 91, wherein it is provided with a piston 92. The rear end of the cylinder 91 receives a cap 93, the firing of which will force the piston 92 and rod 90 forward, thus moving the lever 50 7^a to the dotted line position of the lever 7 of Fig. 3. The cap is fired by a pin 94 slidably mounted in a casing 95, which is united with the cylinder 91. The firing pin carries a collar or cross-piece 96, between 55 which and the rear end of the casing 95 a compression spring 97 is confined, tending to drive the firing pin 94 forward against the cap 93. The firing pin is normally held in its retracted position by means of a lateral 60 stud 98 on the collar 96 occupying a lateral extension or rest 99 at the end of a longitudinal slot 100 in the wall of the casing 95; consequently turning the firing pin 94 will release it to be driven forward by the 65 spring 97. This turning movement of the

firing pin may be effected by a suitable handle, such as indicated at 101, this handle being united with a longitudinal rod 102, the forward end of which is provided with a lateral pin or stud 103 which operates in a longitudinal slot 104 of an extension 105 of the firing pin rod 94. This form of connection enables the firing pin to be turned by the handle 101 without the handle partaking of the longitudinal movement of the firing pin 75 under the action of the spring.

Upon the lower end of the hanger iron 3 is hinged a hollow member 21, which receives a rear stem 22 on the torpedo and constitutes a means for carrying and actuating a tripping or firing member 23. The pivoted end of this tubular member or holder is seen slotted at 24 to accommodate the hanger iron, and the two are connected by a transverse pivot pin 25. The torpedo stem 22 is 80 connected to the holder, after being entered therein, by a shear pin 26, which is passed through registering holes in the parts. This connection is destroyed, and the torpedo consequently freed, by the power developed by 85 the downward swinging of the torpedo, when its front end is released; and to this end the front edge of the extension of the hanger 3 below the hinge axis is formed as a cam or eccentric 27, the form and relation of which 90 to the stem 22 are such that at a predetermined point in the downward swing, at or near the vertical position of the bomb, the rear end of the stem riding forcibly upon the fixed cam thrusts the stem downward 95 and outward in the holder, thereby shearing off the pin 26 and permitting the torpedo to drop. While this construction is preferred 100 for its simplicity, convenience and reliability, I do not necessarily limit myself thereto, 105 since other forms of hinge support for holding the rear end of the torpedo while it swings downward, and for freeing it at a definite time after other instrumentalities have been actuated, may be provided.

In general form and internal construction the torpedo may follow known practice, and such matters are therefore not illustrated or described in detail. The forward stem 8 may contain a firing pin 28, which is normally 110 fixed but adapted to be driven rearward by impact, so as to fire a cap or cartridge 29, which will ignite a detonator inside a tube 30, which detonator will explode the main charge. This firing pin is normally held 115 against movement by a transverse shear pin 28^a passing through it and having its ends received in openings in the fixed tubular part of the stem. The forward portion of the firing pin projects beyond this fixed tubular part in order that it may strike the ground or other obstacle, so as to be driven 120 rearward as the shear pin gives way.

The constructions and arrangements for 125 firing at the rear end of the torpedo in 130

volve important features of novelty. Here also there is a detonator 31 capable of setting off the body of explosive in the interior. This detonator may be ignited by means 5 of a time fuse 32, disposed circularly, that is to say in an arc, in a disk 33 forming part of a fuse-container secured on the rear end of the torpedo at the base of the stem 22. This container has an arcuate groove 34 in 10 its front face, which communicates with the rear face by a series of definitely located flash ports 35. At the regions of these ports the covering of the fuse may be removed and quick match composition applied to insure 15 the action of the fuse. One end of the groove 34 is connected by a radial groove 36 with a central opening 37, through which the fuse is led to the detonator 31. The fuse container is completed by another disk 20 33^a, also provided with a central opening, and which is screwed into a flange 71 on the front face of the disk 33, a plate 72 of vitreous material being preferably interposed between the two disks, closing the face of the 25 groove 34. A flange 73 on the rear end of a copper tube 74 containing the detonator is also clamped between the disks 33 and 33^a of the fuse container, the detonator projecting forward through the central opening in the 30 disk 33^a so as to enter the interior of the bomb. The stem 22 is united or secured in rearward projecting relation to the disk 33, and the disk 33^a has a central forwardly disposed threaded boss 75, whereby the entire 35 unit may be secured to the suitably recessed rear end of the torpedo.

On the lower or forward end of the hinged holder 21 is a timing head 38, which is also in the form of a disk of approximately the 40 same diameter as the fuse container 33. When the torpedo is in the frame, these two parts are held face to face; and one of them is mounted rotatably. Preferably the head 45 38 is secured to the holder in such manner that it may be turned thereon without movement lengthwise. Tongue and groove formations 33^b, 38^b on the disks 33 and 38 serve to prevent entrance of water between them. The head 38 is cut away or recessed at one 50 side, as at 39; and in this recess is a firing block 40 containing a cap seat 41 and a flash passage 42 to register with any one of the ports 35. The flash passage 42 terminates in a projecting nipple 43 on the forward 55 or inner face of the rotatable head, adapted to enter said ports and to hold the parts in fixed relation when once adjusted. To permit of the adjustment the firing block bearing the nipple or registering projection is 60 mounted on the timing head disk in such manner that it may yield away from the fuse container, while being normally pressed thereto. This is accomplished by connecting the end of the block 40 adjacent the center 65 to the head 38 by means of a transverse

pivot pin 44. An expansion spring 45 confined between the block and a bracket 46 on the head urges the block against the fuse container 33, or to a position in which the nipple will enter a port. The ports not 70 in registry with the nipple at any time are covered by the timing head disk 38. A handle 47 projecting from the block 40 facilitates the turning of the head about the axis of the holder 21 and stem 22, and the 75 movement of the block away from the fuse container to disengage the nipple. The nipple 43 is preferably located eccentrically with respect to the chamber of the flash passage, and the front or lower wall of this 80 chamber is formed with a cavity 42^a having a vent opening 42^b, the cavity being in line with the cap 48, so that when the latter is fired its wadding will be caught in the cavity and will be prevented from obstructing the 85 nipple.

The cap 48, which is placed in the seat 41 in the firing block, is fired by a hammer 49, the head of which is secured to the end of a flat spring 50, which in turn is secured to the 90 bracket 46. The spring 50 is normally not under firing tension, so that there is no danger of its being accidentally released and flying against the cap, and in addition the cap is protected by a safety pin 51, which is 95 inserted through holes in the block 40 over the cap in position to prevent the hammer touching the cap as long as the pin is in place. This pin may be in the form of a cotter pin with a large and conveniently 100 accessible ring handle 51^a, and is held frictionally in place and may be readily withdrawn by the pilot before pulling the launching lever 11.

The hammer 49 is retracted and released 105 by the tripping member 23 heretofore referred to as being mounted on and operated by the holder or hinged member 21. The said member 23 is desirably constructed as a collar slidingly encircling the holder and 110 having a rim 52 which contacts with the tip 53 of the hammer and draws the same rearward when the collar itself is drawn rearward or upward on the holder. Continuance of the movement carries the rim 52 from beneath the extremity of the hammer, and the latter is then driven by its spring against the cap 48. The movement of the tripping member upward and rearward on the holder is brought about as the result of the downward swinging of the holder and the connection of the tripping member with a fixed point above the hinge axis 25, the said connection being a pull link or pair of links 54, pivoted at 55 to the tripping member and 120 at 56 to the hanger 3.

In addition to the time fuse firing mechanism just described and the impact firing device at the forward end of the torpedo, another firing member is provided at the 130

rear, adapted to be actuated upon contact of the torpedo with a more or less yielding body. This second firing pin or plunger 57 is mounted to slide in the rear stem 22 and 5 operates by inertia, which causes the plunger to continue downward against the resistance of a relatively weak spring 58, after the torpedo and its stem have been stopped in a more or less cushioned manner by encounter 10 with a dirigible, an observation balloon, another plane or protective nets such as are placed over some buildings. The device will, of course, also operate in event of the bomb striking the earth or an unyielding 15 obstacle. Normally the plunger 57 is barred against forward movement by a safety shear pin or screw 59, which passes through the wall of the stem 22 into the plunger. The rear portion or tail 60 of the plunger is extended past the shear pin 26, heretofore described and which it accommodates in a slot 61, and beyond the rear end of the stem 22, in position to be acted upon by the cam 27, in advance of the action thereof upon the 20 stem, so that the screw 59 is sheared and the inertia plunger 57 released before the torpedo is freed from the hinge support. The said plunger acts upon a cap 62 in or adjacent the base of the stem 22, which cap is 25 arranged to fire the detonator 31, to which the time fuse 32 also leads. As shown this cap is placed in a seat 62^a, which is screwed through the opening 37 of the disk 33, which is threaded for the purpose, into the interior 30 of the stem, which is formed as a continuation of said opening and which is threaded for a short distance in rear of the disk. Air release holes 62^b are formed in the wall of the stem behind the cap so that forward 35 movement of the striker will not be opposed by an air cushion.

In operation, each torpedo is carried horizontal as stated. The shear members 26 and 59 and the withdrawable safety pin 51 are 40 all in place. To launch the torpedo and to place it in condition to explode, the aviator sets the timing head 38, draws out the pin 51 and pulls the lever 11. The latter operation moves the slide or longitudinally extending connection 14, and shifts the rest lever 7 from beneath the forward stem 8 of the torpedo. The torpedo immediately swings down upon its rear hinge support, and this movement actuates the link-held 55 tripping member 23 in the manner already described. The hammer 49 is pulled back and let go, and thereupon drives forward upon the cap 48, which is fired, its flame striking through the passage in the block 60 40 and through the registering port 35 to the time fuse 32, which it ignites. This occurs before the pin 26 is sheared and while the torpedo is still connected to the hinge support. Also, before the said connection 65 is broken, the shear member 59 is destroyed

by the coaction of the plunger 57 and the cam 27, so that this inertia firing member is free to act upon contact to explode the detonator 31, if at that time it has not already been set off by the time fuse. Finally, the 70 pin 26 is sheared and the torpedo drops away, with its time fuse burning and its impact firing devices in condition to operate. When the torpedo falls from the plane it carries the fuse container with it, but the 75 timing head is left behind upon the hinge fixture, of which it forms a part.

In order to set the time fuse to explode at any height the operator merely tilts the block 40 away from the fuse container 33 80 and turns the timing head 38 by means of the handle 47 until a pointer 63 coöperating with index marks 64 indicates the desired elevation. Then the handle is released and the firing block snaps into registry with one 85 of the flash ports 35. In case the aviator intends the torpedo to explode only upon contact, he can turn the head 38 so that the flash port 42 is opposite a blank portion of the fuse-holder disk 33, in which event the fuse 90 will not be ignited.

Figs. 14-17 illustrate a modified construction, wherein the shear pin 26 is replaced by a separable hinge construction. The lower end of the hanger-iron 3^a is narrower than the hanger 3 of the other form and is embraced by rearwardly extending bifurcations 80 upon the stem 22^a of the torpedo. These bifurcations are apertured by transverse pivot openings 81, from which slots 82 extend rearward to the end of the stem. The pivot pin 25^a is slabbed off at opposite sides 83 and is held against turning in the hanger 3^a by reason of the fact that the opening in this member is correspondingly formed; or other means may be provided for securing the pivot pin with the greater width of its slabbed portion at an inclination to the vertical. With this construction it will be seen that when the torpedo is in the horizontal 100 position the hinge is locked, but when the torpedo swings downward to or near the vertical position the stem 22^a can drop away from the hinge pin 25^a, because the exits 82 are then opposite the narrow transverse dimension of the slabbed-off pivot pin. These exits must be wider than the narrow dimension of the pin and narrower than the greater transverse dimension thereof. In order to facilitate assemblage the pin 25^a 110 may be made removable, being held in place by a cotter-pin 84. In this construction the principal function of the holder 21^a is to serve as a mounting and guide for the tripping member 23. In other particulars this form may resemble the one previously described.

What I claim as new is:

1. Launching means for aerial torpedoes comprising a hinged holder for one end of 130

- the torpedo, a withdrawal support for the opposite end, together supporting the torpedo horizontal, a shear pin uniting the torpedo and hinged holder, and means whereby downward swinging movement of the torpedo and hinged holder automatically causes the shearing of said pin.
2. Launching means for aerial torpedoes comprising a stem on the rear end of the 10 torpedo, a hanger, a holder hinged to the hanger and receiving said stem, a shear pin connecting the stem and holder, a withdrawable support for the forward part of the torpedo between which and the holder 15 the torpedo is held horizontal, and a cam on the hanger below the hinge axis adapted to act upon the stem to shear the pin when the torpedo and holder swing downward.
3. In launching means for aerial torpedoes, the combination of a hinged holder for the rear end of the torpedo, releasing means 20 coöperating therewith to support the torpedo horizontal, an inertia firing device in the rear end of the torpedo, a safety shear member barring movement of said firing device, a 25 safety shear member connecting the torpedo and holder, and means for automatically shearing both said safety members as the result of downward swinging of the torpedo 30 and holder.
4. In launching means, the combination of a stem on the rear end of the torpedo, an inertia firing device in said stem, a hinged holder receiving the stem, releasing means 35 coöperating with the hinged holder to support the torpedo horizontal, a safety shear member connecting the torpedo stem and holder, a second safety shear member securing said firing device, and a stationary 40 cam disposed so as to force downward upon both the stem and the inertia firing device, to shear their members, when the torpedo and holder swing down.
5. In launching means for aerial torpedoes, the combination of a hinged holder for the rear end of the torpedo, releasing means 45 coöperating therewith to support the torpedo horizontal, an inertia firing device in the rear end of the torpedo, a safety shear member barring movement of said firing device, a safety shear member connecting the torpedo 50 and holder, and means for automatically shearing said members in succession as the result of downward swinging of the torpedo 55 and holder.
6. In launching means for aerial torpedoes, the combination of supports for the front and rear of the torpedo together carrying the same horizontal, one of the supports being a hinge support and means for 60 withdrawing the other, means whereby the torpedo is automatically freed from the hinge support when it has swung downward, an inertia firing device in the rear part of the 65 torpedo, a safety connection normally hold-
- ing said firing device, and means for destroying said connection by the downward swinging movement of the torpedo.
7. In launching means for aerial torpedoes, the combination of supports normally 70 carrying the torpedo horizontal, one being a hinge support and the other a withdrawable support, an inertia firing device in the torpedo, means normally securing said device, and means whereby the firing means is 75 automatically relieved of the restraint of said securing means when the torpedo swings downward.
8. In launching means for aerial torpedoes, the combination of supports normally 80 carrying the torpedo horizontal, one being a hinge support and the other a withdrawable support, an inertia firing device in the torpedo, a shear member normally barring forward movement of said firing device, and a 85 cam for shearing said member when the torpedo swings downward.
9. In launching means for aerial torpedoes, the combination of supports normally 90 carrying the torpedo horizontal, one being a hinge support and the other a withdrawable support, an inertia firing device in the torpedo, a shear member normally barring forward movement of said firing device, and a fixed cam below the hinge axis, the relation 95 of the cam and firing device being such that the firing device is caused to ride forcibly upon the cam when the torpedo swings downward, thereby shearing said member.
10. In launching means for aerial torpedoes, the combination of a hinge support for the rear end of the torpedo, a withdrawable support coöperating therewith to support the torpedo horizontal, means whereby the 100 torpedo is freed when it has swung downward, a spring-driven firing hammer, and means for tripping the hammer as the result of the downward swinging movement of the torpedo.
11. In launching means for aerial torpedoes, the combination of a hinge support for the rear end of the torpedo, a support for the forward part of the torpedo coöperating 110 with the hinge support to carry the torpedo horizontal, means for withdrawing the forward support, a time fuse, firing means therefor actuated by the downward swinging movement of the torpedo, a connection uniting the torpedo to the hinge support, and means for breaking said connection 115 when the torpedo has swung downward.
12. In launching means for aerial torpedoes, the combination of a stem on the rear end of the torpedo, a hinge fixture including a pivoted member receiving said stem, 120 a connection uniting the stem with the hinge fixture and means whereby said connection is broken when the torpedo swings downward, releasing means coöperating with the hinge fixture to support the torpedo hori- 125
- 130

zontal, a time fuse disk at the base of said stem on the torpedo, a rotatable timing head on the pivoted member of the fixture, an ignition hammer on said turning head, and 5 means whereby said hammer is actuated by downward swinging of the torpedo and member.

13. In launching means for aerial torpedoes, the combination of means comprising 10 a hinge fixture and a withdrawable support for carrying the torpedo horizontal, a connection uniting the torpedo to the hinge fixture, means whereby said connection is broken by downward swinging movement, a 15 time fuse carried by the torpedo, means for igniting the same comprising a spring-driven firing hammer on the hinge fixture, a tripper on the fixture, and a link connecting said tripper with a point above the hinge 20 axis.

14. In launching means for aerial torpedoes, the combination of a hinge fixture for the rear end of the torpedo, releasing means coöperating with the hinge fixture to support the torpedo horizontal, means whereby the torpedo is disconnected from the hinge fixture at a predetermined point in the downward swinging movement, a time fuse carried by the torpedo, means for igniting 25 the same including a member slidable on the swinging part of the hinge fixture, and means whereby said member is caused to slide thereon by the downward swinging movement.

30 15. In launching means for aerial torpedoes, the combination of a stem on the rear end of the torpedo, a hinge fixture having a pivoted holder receiving said stem, a connection uniting the stem with the fixture, releasing means coöperating with the hinge fixture to support the torpedo horizontal, means whereby said connection is broken by downward swinging movement, a time fuse carried by the torpedo, means for igniting 35 the same comprising a spring-driven firing hammer on said holder, a slidible tripping collar encircling the holder and stem, and a link disposed to pull the collar upward on the holder as the latter swings 40 down.

16. In launching means for aerial torpedoes, the combination with an aerial torpedo, and a fixture from which the torpedo is launched, of a time fuse container on the 45 torpedo, a circularly disposed fuse in said container, and firing means on the fixture, said fuse container and firing means being relatively rotatable.

50 17. In launching means for aerial torpedoes, the combination with an aerial torpedo, and a fixture from which the torpedo is launched, of a time fuse container on the 55 torpedo, a circularly disposed fuse in said container, a cap-receiving firing block on the fixture in juxtaposition to the fuse con-

tainer on the torpedo, and a hammer co-operative with the firing block, the firing block and its hammer on the one hand and the fuse container on the other hand being relatively rotatable.

70 18. In launching means for aerial torpedoes, the combination with an aerial torpedo, and a fixture from which the torpedo is launched, of a time fuse container on the torpedo having a face formed with a circularly arranged series of flash ports, a cap-receiving firing block on the fixture in juxtaposition to said face, and a firing hammer, the firing block and hammer on the one hand and the fuse container on the other 75 being relatively rotatable.

80 19. The combination with an aerial torpedo, and a fixture from which the torpedo is launched, of a time fuse container on the torpedo having a face provided with a circularly disposed series of flash ports, a firing block normally in juxtaposition to said face and having a nipple terminating its firing passage and adapted to enter said 85 ports, a mounting for the firing block on the fixture permitting it to be separated from the ported face to disengage and re-engage the nipple with one or other of the ports, the firing block and fuse container being in addition relatively rotatable, and 90 a spring for pressing the firing block toward the face.

95 20. The combination with an aerial torpedo, and a fixture from which the torpedo is launched, of a time fuse container on the 100 torpedo having a face provided with a circularly disposed series of flash ports, a timing disk rotatably mounted on the fixture and covering said face, a firing block carried by said timing disk and provided with 105 means for registering its firing passage with one or other of said ports, the firing block being yieldingly mounted in the timing disk for disengagement and reengagement with the ported face.

110 21. The combination with an aerial torpedo, and a fixture from which the torpedo is launched, of a time fuse container on the torpedo having a face provided with a circularly disposed series of flash ports, a timing disk rotatably mounted on the fixture and covering said face, a firing block disposed in a recess of the timing disk and hinged thereto on an axis parallel with the ported face, means for registering the firing 115 passage of the firing block with any one of said ports, and a spring pressing the firing block toward the face.

120 22. The combination with an aerial torpedo, and a fixture from which the torpedo is launched, of a time fuse container on the 125 torpedo having a face provided with a circularly disposed series of flash ports, a timing disk rotatably mounted on the fixture and covering said face, a hammer on said 130

disk, a firing block yieldingly mounted therein, and means for registering the firing block with the ports.

23. Carrying and launching means for aerial torpedoes, comprising end hangers, means for hingedly connecting the rear end of the torpedo to one hanger, the opposite hanger having a recess with a bottom exit for receiving a projection on the forward 10 end of the torpedo, a horizontally swinging lever rest closing the bottom of said recess, a releasing lever adjacent the hinge hanger, and a connection extending from said releasing lever to the lever rest.

15 24. A carrying and launching frame comprising end hangers, means for hingedly connecting the rear end of the torpedo to one hanger, the opposite hanger having a recess with a bottom exit for receiving a 20 projection on the forward end of the torpedo, a withdrawable rest closing said exit,

a substantially vertical releasing lever fulcrumed on the frame adjacent the hinge hanger, and a slide on the upper part of the frame connected at one end to said releasing lever and having a connection at the other end extending downward to the withdrawable rest. 25

25. In launching means for aerial torpedoes, the combination of means for carrying the torpedo horizontal including a hinge support for the rear end of the torpedo, means for releasing the torpedo to swing downward, means whereby the torpedo is freed when it has swung downward, a 30 spring-driven firing hammer, means for tripping the hammer as the result of the downward swinging movement of the torpedo, and a safety member normally interposed between the hammer and the part 40 upon which it is to act.

JOSEPH MENCHEN.
